Patented July 2, 1918.

INVENTOR
FRANK C. STOWELL
BY *Miss Speare Jr.*
ATTORNEY

UNITED STATES PATENT OFFICE.

FRANK C. STOWELL, OF MEDFORD, MASSACHUSETTS.

VENTILATOR.

1,271,238.

Specification of Letters Patent.

Patented July 2, 1918.

Application filed June 25, 1915. Serial No. 36,364.

To all whom it may concern:

Be it known that I, FRANK C. STOWELL, a citizen of the United States, residing at Medford, county of Middlesex, Commonwealth of Massachusetts, have invented certain new and useful Improvements in Ventilators, of which the following is a specification.

This invention relates to ventilators and particularly to a ventilating equipment for moving vehicles, such as street railway cars and the like.

The ventilating system of a street railway car usually consists of a series of external air intake members, a series of internal controlling members for regulating the passage of the admitted air into the car, and a series of intermediate air conducting members.

The present invention relates particularly to the construction and arrangement of these intermediate air ducts, and contemplates an air duct which will be capable of easy installation between the outer and inner members and will positively prevent passage of snow, water, and the like into the car. Prior to my invention, these intermediate members have simply been permanently secured, by soldering or otherwise, to the outer members, and by reason of their inaccessible location it has been not only a matter of considerable difficulty to solder them in position, but when once soldered it has been practically impossible to remove them. Moreover, the form of the air ducts has been such as to actually direct water into the car instead of excluding it.

In carrying out my invention, the external air inlet member is provided with a flange along one or more edges adapted to receive one or more edges of the intermediate conducting member and said conducting member is provided with one or more flanges adapted to receive opposite edges of the outer member. The whole provides a slidably interlocking structure which can be readily assembled and taken apart. The delivery end of the conducting member is detachably fastened in any suitable manner as by screws or the like to the inner "skin" of the car in communicating relation to the interior air controlling shutters. The bottom wall of the air duct is sloped downwardly and outwardly so that any

water which finds access thereto through the exterior member is directed downwardly and outwardly into said member.

The construction and operation of my device will be more fully disclosed in the specification that follows. In the drawings forming a part of that specification I have shown as an illustrative embodiment a form of ventilator which has been found satisfactory in use and well adapted to the requirements of manufacture.

Throughout specification and drawings like reference numerals are correspondingly applied, and in these drawings:

Figure 1 is a transverse section through a car roof equipped with my invention.

Fig. 2 is an end view of the air duct illustrating its manner of connection with the outer member, and

Fig. 3 is a partial view of the underside of said duct.

I have indicated at 1 an air intake member adapted to be secured to the car wall 2 near the roof. The member 1 may be of any desired construction and is preferably of the construction shown in the drawings. The inner face of the member 1 has one of walls 3 (shown as the bottom wall in the drawings) extending upwardly and inwardly toward the interior of the car. The free edge of the wall 3 is turned over upon itself as indicated at 4 to provide a rolled edge. The opposite top wall and the end walls of the member 1 extend inwardly toward the interior of the car as flanges 5.

Secured to each flange 5 by solder or otherwise is a U-shaped strip 6. Each strip 6 is bent over the free edge of the flange 5 to provide a rolled edge 7. The strips 6 slidably receive the straight, unformed edges 8 of three sides of an intermediate air conducting member 9 disposed between the car wall 2 and the inner skin 10 of the car and secured at its inner flanged end 9¹ to the skin 10 in any suitable manner as by the fastenings 11.

The fourth edge of the air duct 9 is formed for interlocking engagement with the wall 3 of the intake member 1 by turning said edge over and back upon itself and then outwardly as indicated at 12. This provides a continuous recess in which the rolled edge 4 of the wall 3 is slidably received.

The opposite end of the member 9 de-

2
livers to the air controlling members 13 secured to the skin 10 within the car by the fastenings 11. These members 13 are preferably shutters slidable one upon the other 5 and operated by an actuating rod 14.

The bottom wall of the member 9 is sloped downwardly and outwardly as shown. At its delivery end the member 9 is deflected laterally as indicated at 15 to 10 enable it to be attached to the skin 10 without piercing said member.

The arrangement is such that water or the like entering the member 9 through the member 1 flows down the downwardly inclined bottom wall of the member 9 back 15 into the member 1. This prevents ingress of the water into the car.

In assembling the device of the present invention, the members 9 and inner shutter 20 13 are secured to the skin 10 by means of the fastenings 11. The outer member 1 is then interlockingly engaged with the outer end of the member 9 by means of the strips 6 and flange 12 which receive opposite edges of 25 said members 1 and 9. The outer member 1 is then secured to the wall 2 by suitable fastenings. This interlocking engagement of the members 1 and 9 therefore not only permits a ready assembling of the members but 30 enables them to be disseminated easily for the purpose of repair or the like. It will be understood that the members 1, 9 and 13 are mounted in longitudinal series along each 35 side of the car. The specific constructions of the members 1 and 13 forms no part of the present invention except in so far as they combine with the intermediate member 9.

While I have shown the members 1 and 9 as each having one or more locking devices 40 for the reception of opposite edges of said members, it will be understood that if desired all the locking devices might be formed on one or the other of the members and the opposite member simply have straight unformed edges slidable into said devices. 45 Similarly, it will be evident that either member may have a greater or less number of

locking devices than the number shown and that their arrangement may be varied.

These and various other modifications of 50 my device may be resorted to, all without departing from the spirit of my invention, if within the limits of the appended claims.

What I therefore claim and desire to secure by Letters Patent is: 55

1. A ventilator for a vehicle having a double wall consisting of an air intake member fastened to the outer member of the wall and having certain of its edges flanged and extending into the space between the members of the double wall, double folded strips secured to said flanges, and an air duct arranged in the space between said double wall and secured at its inner end to the inner member of said double wall and having 60 certain of its edges at its outer end unformed and adapted to slidably fit in the recesses provided by the double folded devices of said intake member. 65

2. A ventilator for a vehicle having a double wall consisting of an air intake member adapted to be fastened to the outer member of the wall and having an unformed edge and flanged edges all extending into the space between the members of the double 70 wall as flanges, double folded strips secured to said flanges, and an air duct arranged in the space between said double wall and secured at its inner end to the inner member of said double wall and having certain of 75 its edges at its outer end unformed and adapted to slidably fit in the recesses provided by the double folded devices of said intake member and having a single edge at said outer end bent back upon itself to receive said unformed edge of the intake member. 80 85

In testimony whereof I affix my signature in presence of two witnesses.

FRANK C. STOWELL.
